SHOE UPPER

Jacob F. Jonas, Bellevue, Ky., assignor to The Krippendorf-Dittmann Company, Cincinnati, Ohio, a corporation of Ohio

Application May 31, 1939, Serial No. 276,544

1. Claim. (Cl. 36—55)

This invention relates to improvements in shoes, and particularly to the throat portion of a pump high heel style of lady's shoe.

An object of the invention is to provide the lining of a shoe with a distensible throat to obtain a more snugly and higher fitting throat for more securely holding a pump style of shoe to the foot and one which will comfortably yield to ordinary maneuvering of the foot while walking.

Another object of the invention is to provide a double lined shoe with a distensible insert or goring for the throat portion of the inner lining, and with the middle lining cut away within the region of the insert to minimize the laminations of the upper at the throat, and to avoid any obstructing bunching of the material irritating to the foot and effecting discomfort to the wearer.

Other features and advantages of the invention will be more fully set forth in a description of the accompanying drawing, in which:

Figure 1 is a perspective view of an assembled composite lining with an elastized throat section secured to the rear margin of the vamp lining.

Figure 2 is an interior view of a lining assembly shown in Figure 1.

Figure 3 is a section on line 3—3, Figure 1.

Figure 4 is a perspective view similar to Figure 1, illustrating a margin at the inner end of the throat section turned or hemmed over upon the upper or outer side of the section.

Figure 5 is a section on line 5—5 of Figure 4.

Figure 6 is a perspective view of the throat portion of a vamp in the process of applying and turning over an edge covering binding.

Figure 7 is a section on line 7—7 of Figure 6.

Figure 8 is a central section through the vamp of an assembled upper ready for drawing over a last and the application of a sole.

Figure 9 is an enlargement of Figure 8.

The improvement is particularly adaptable and advantageous for a double-lined high-heel pump type of shoe to obtain a snug high-fitting yielding or elastic throat portion, non-irritating to the foot of the wearer. It, however, is not intended by the exemplification to so limit the invention as it is obvious that it may be incorporated in other styles or types of construction of shoe.

The drawing illustrates in separate views various components of a lined shoe upper, and different steps in the making thereof and assembly up to the completed upper ready for drawing over a last and the application of an outer sole,

and the illustrations follow as nearly as possible an orderly procedure as carried out in the factory to aid in a more ready understanding of the invention.

Referring to the drawing, 1 indicates a vamp lining section preferably of a drill fabric, cut to the required pattern with the throat edge 2 cut definitely low or inward from that of the prevailing practice. The margin of each of the opposite rearwardly extending portions 3, 3, of the vamp lining section is overlappingly joined and secured by a double row of stitching 4 to the corresponding forward margin of the quarter lining sections 5, 5, usually of a leather material. The rear margins of the quarter lining sections, one for each of the opposite sides of the shoe, are overlappingly joined and secured by stitching to the inside heel section 6, usually of leather and of a different grade than that of the quarter sections.

The forward extremities of the quarter linings are joined and bridged by an elastized throat section 7, overlappingly joined to the throat margin of the vamp lining and to the underside thereof and secured thereto by a continuation of the double line of stitching 4 which joins the vamp lining to the quarter linings. The throat section 7 is also stitched to the quarter linings respectively by a line of stitches 8.

The elastic throat forming section 7 constitutes a piece of fabric having one side rubber or gum coated as shown at 7a, the coating having been applied while the fabric was stretched or held under tension so that when the coating set the fabric is contracted by the elastic coating. Aside from its mode of manufacture, which need not herein be further explained as it represents a commercial product readily available, it possesses as a characteristic that it is elastic and yields in all directions, and is more yielding transversely of the shoe than longitudinally thereof. Therefore, in its use in a vamp, it provides for considerable flexibility crosswise of the throat. It serves to permit extending the throat upwardly, thus coming up higher on the instep and snugly lying over the instep so that the shoe is more securely fitted to the foot and without discomfort to the wearer.

The elastic section 7 has its free or inner margin 9 folded upon itself or hemmed over for its length between the top edges of the quarter lining sections, and adhesively secured, the gum or rubber coating 7a of the material serving for that purpose, and, as shown in Figures 1 and 4, 55 the coated gum side of the section is disposed

uppermost so that the fabric surface is exposed to the inner side of the shoe. The hem or fold forms a finished edge which registers with the corresponding edge of the vamp and to which it is stitched.

As shown in the inside view, Figure 2, the top edge of the quarter sections extend approximately in a straight line and continue so to their forward extremities 10 which are secured to the vamp lining section 1 so that the elastic or distensible goring section 7 forms a crosswise connection for the forward extremities of the quarter sections and an elastic throat extension for the vamp lining section 1.

The vamp 11 is provided with a double or middle lining which corresponds in pattern outline substantially therewith, excepting that it is cut short at the throat as shown at 12, Figures 7, 8, and 9, to more than clear the hem of the elastic throat section 7. The top edge of the quarter sections and the coinciding edge of the lining therefor, as a laminated unit from the throat rearwardly and on the inside thereof, are reinforced by a binding tape 13. The binding tape is adhesively secured to the top margin of the lining and has an edge coinciding with the edge of the quarter sections. This provides reinforcement for the edge of the upper of the shoe from the throat rearwardly and around the heel. The throat edge of the vamp is bound in a usual manner with the conventional French binding 14 which has an adhesive coated margin of gum or rubber, rendered plastic by the application of heat, or a pressure sensitive adhesive on an inner face.

The binding 14 initially is applied in the usual manner by initially disposing the same upon the outer side of the vamp with an edge in alignment with the edge of the throat thereof, and the parts secured by an edge line of stitching 15. The binding extends around the throat edge of the vamp only, due to the middle lining being cut short at this portion. After the stitching, the binding is turned inwardly over the raw edges of the several parts and adhesively overlappingly secured to the inner binding tape 13, and for the throat is secured directly upon the inner side of the vamp. In some instances, after the French binding has been turned inward, the parts are further secured by a line of stitching running parallel with the bound edge and marginally inward thereof.

The lining composed of the vamp, quarter and heel sections is inserted within the upper, and,

as the quarter and heel sections are of leather, their raw top edges adjoin the bound edge of the vamp, and the parts are secured together by a line of stitching 16 extending along the fold of the binding, giving a beaded effect to the binding. The stitching extends around the throat joining the vamp with the elastic throat section 7, and in a manner non-interfering to the elasticity of the throat.

At the throat the upper constitutes a leather vamp, the French binding with its elastized margin, which gives it elasticity or distensibility longitudinally, and the elastized throat section 7 affords a minimum number of laminations which are expanded in drawing the upper over a last and elastically contract when removed from the last, leaving the throat extremely flexible for snugly fitting across the foot of the wearer of the shoe, and permits the throat of the shoe to be brought up sufficiently high for holding the shoe against slip upon the foot in walking.

The distensible insert or goring for the lining preferably is of an extremely fine thread woven fabric, and in the manner applied presents no obstruction irritating to the foot of the wearer, and provides ample yield for the wearer to conveniently and with ease remove or apply the shoe upon the foot.

A high-heel pump style of shoe makes a very attractive product, and as the improvement provides the necessary elasticity at the throat, the heel of the foot can be considerably elevated by high heels for the shoe without discomfort to the wearer. The throat conforms to the foot in a manner which will securely hold the shoe to the foot in walking without extraneous tie straps or the like.

Having described my invention, I claim:

In a shoe of the pump type, a vamp, a lining for the vamp, said lining having a throat section of distensible fabric material fixed thereto, said throat section being of a type in which the fabric under tension is coated on one side with an elastic medium, said section underlying the throat portion of the vamp, the throat end of the section being overlapped to provide a folded throat edge in registry with the throat edge of the vamp, the lap extending inwardly between the vamp and body portion of the section, and the folded portion of the section being secured to the vamp by stitching extending in a line along the throat edge.

JACOB F. JONAS.
